HAROLD E. WHITE, OF WILKINSBURG, PENNSYLVANIA, ASSIGNOR TO WESTINGHOUSE ELECTRIC & MANUFACTURING COMPANY, A CORPORATION OF PENNSYLVANIA

LOCKOUT SWITCH

Application filed January 2, 1926. Serial No. 78,804.

My invention relates to electromagnetic switches and it has particular relation to switches of the lockout type.

An object of my invention is to simplify the construction and improve the operation of lockout switches.

Another object of my invention is to provide a switch of such character that its operativeness shall not be materially affected by vibration and shocks produced by external sources.

Other objects of my invention will become apparent in the following specification and claims appended thereto.

15 In the use of switches of the lockout type, difficulty is sometimes experienced, on account of premature closure of the switch, as the result of vibrations of such magnitude that the flux induced by the current fails to 20 properly lock out the switch armature. Another reason for such failure is inherent in the construction of the majority of switches in that the lockout point, or point at which the switch armature is released, is not clearly defined.

In accordance with my invention, I utilize the saturation phenomena in magnetic iron to improve the stability and general performance of the magnetic switch. I provide 30 a magnetic shunt of material, such as soft iron, of relatively high permeability. This shunt is located in the air gap between the armature of the switch and its lockout magnet. At a predetermined value of current 35 traversing the coil of the lockout magnet, the magnetic shunt becomes saturated and the additional flux, or leakage flux, traverses the magnet armature which, in its initial position, is in engagement with the shunt member.

40 I have discovered that, for all values of current above this saturation point, the switch armature is positively sealed and restrained from closing, whereas, if current in 45 the coil decreases to a point where the shunt member is no longer saturated, the armature is no longer restrained and the switch is permitted to close under the operation of the closing force.

50 My invention will be best understood by

reference to the accompanying drawing, in which

Figure 1 is a view in side elevation of a two-pole, or double-coil, switch of the lockout type;

55 Fig. 2 is a diagrammatic view of a modified form of the switch illustrated in Fig. 1, incorporated in a system of motor control;

Figs. 3 and 4 are views in side elevation 60 and in plan, respectively, of a multiple-finger accelerating relay incorporating the peculiar features of my invention.

With reference to Fig. 1, it will be observed that the switch, in its main structure, corresponds to common practice, such as the switch illustrated in the Deutsch Patent No. 1,339,922, issued May 11, 1920 and assigned to the Westinghouse Electric & Manufacturing Company. The lockout magnet of my 70 switch, however, differs from the Deutsch switch as will be described.

A pivotally mounted armature 1 is normally biased by the action of gravity to the illustrated lockout position, and is designed 75 to be restrained in that position by means of a lockout magnet comprising a core member or pole-piece 2 and an operating coil 3. A closing coil 4 is provided to actuate the armature 1 against the bias of the lockout 80 coil 3. Movable and stationary contact members 5 and 6, respectively, of any suitable character are employed.

A magnetic shunt member 7, in the form of a U-shape strip of relatively thin soft iron, 85 is so constructed as to carry flux traversing the core member 2. The shunt member is preferably in contact with the inner end of the pole piece 2 and extends into the air gap 90 between the other end of pole piece 2 and the armature member 1. As illustrated, the lower end of the armature 1 rests against a portion of the shunt 7. The air gap of the switch is adjusted by means of a compression 95 member comprising a stiff spring 8 that bears against shunt 7 and is mounted on a stud 9 traversing a hole 11 in the end of the shunt. The position of the shunt 7, and the initial 100 position of the armature 1, is adjusted by

means of lock nuts 12 that are mounted on the outer end of stud 9.

I have thus illustrated simple means for adjusting the position of the shunt member 7, but any suitable adjustment may be provided whereby the relative positions of the armature and pole-pieces may be adjusted to accurately determine the "setting" of the lockout switch. The setting of the switch may also be changed, of course, by varying the strength 10 of the lockout magnet, as by providing lockout coils of different numbers of turns. I 15 preferably employ a shunt-type coil adapted to be connected across all or any portion of a resistor, such as the accelerating resistor commonly employed for starting motors. When 20 the lockout coil 3 is energized to a low degree, a small amount of magnetic flux traverses the pole-piece 2 and the shunt 7.

By increasing the excitation of the coil 3, a point is reached at which the shunt 7 becomes saturated and is unable to carry all the flux 25 traversing the pole-piece 2, so that the excess flux then traverses the armature member 1 and, on account of the physical contact 30 between the members 1 and 7, the armature is securely sealed in the illustrated position. It will be evident that the pull of the closing coil 4 will be insufficient to operate the switch 35 until its armature is released by reason of a reduction in the excitation of the lockout magnet 3 to a predetermined value, or setting, at which little or no flux from the pole-piece 2 enters the armature 1 and the flux traverses a local circuit comprising the pole-piece and the shunt member 7.

To illustrate the effectiveness of my lockout structure, I found that with one hundred percent increase in current traversing the 40 closing coil 4, a seven percent increase in current in the lockout coil 3 was sufficient to keep the switch from operating. I also discovered that the point at which the switch releases is very accurately defined in contrast 45 to the uncertain operation of many switches heretofore employed.

Fig. 2 illustrates a lockout switch utilizing the same principle of operation as that set forth in connection with Fig. 1, the switch structure, however, being somewhat different. In this instance, the pole-pieces comprise core members 13 and a U-shape member 14 across the open end of which is connected a shunt member 17 comprising a strip of soft iron. 50 The switch armature 21 normally rests upon the shunt member 17 and is disengaged therefrom only through the action of the closing coil 4, which acts in opposition to the lockout coil 3, in a manner previously described. The 55 lockout coil 3 is connected across an accelerating resistor 22, such as is commonly employed for controlling the operation of a motor, for example, the illustrated direct-current motor comprising an armature 23 and a series field-magnet winding 24.

In the form of my invention herein illustrated, the initial or "peak" accelerating current traversing the lockout coil 3 saturates the magnetic shunt 17, and the leakage flux, therefore, traverses the armature member 21. As 70 the motor armature 23 accelerates and the starting current is reduced to a minimum, the flux traversing the pole-pieces 13 and 14 becomes insufficient to saturate the shunt 17, whereupon armature 21 is released and the 75 switch is closed, by the action of the operating coil 4, to short-circuit the starting resistor 22.

In Figs. 3 and 4, I have illustrated my invention as applied to a multiple-finger 80 accelerating relay of the type illustrated in De Camp Patent No. 1,392,249, issued September 27, 1921. This relay, as commonly constructed, is open to the criticism above indicated, in connection with the operation 85 of lockout switches, when subjected to vibration or shocks, if the controllers are mounted on shipboard or on any vehicle, for example.

It is believed to be unnecessary to describe the details and operation of the De Camp 90 relay, since it is clearly described in the above-identified patent. It will be sufficient to note that I have provided a magnetic shunt 27 for each of the successively movable switch members 28, 29 and 30, respectively. Therefore, when the relay coil is over-excited by peak currents, the magnetic flux traversing the pole-piece 10 in part traverses the shunt member 27 and in part the corresponding finger, such as 30, for example; and the finger 100 is restrained in its illustrated position until the excitation of the relay coil is reduced to a minimum, when all the flux traversing the pole-piece 10 can be carried by the shunt member 27, at which time the finger 30 is 105 actuated by the spring 31.

Certain of the minor structural details of the De Camp relay have been modified and simplified, as incorporated in my invention, although the principle of operation and the 110 structure in general remains the same. The simple improvement which I have added is sufficient, however, to greatly improve the operation of this otherwise efficient relay, thereby adapting it to many applications 115 where severe vibration will disturb the setting of relays otherwise constructed in accordance with familiar practice.

My invention has been described and illustrated in preferred forms in connection with 120 switches of a familiar type, and it will be obvious that various other modifications may be made by those skilled in the art without departing from the spirit of my invention. I desire, therefore, that my invention 125 shall be limited only in accordance with the scope of the appended claims.

I claim as my invention:

1. A lockout switch comprising a movable armature member, a stationary pole-piece, a 130

shunt member for deflecting flux from said armature member, a portion of said shunt member being disposed between said pole-piece and said armature member, and means

5 for adjusting the position of a portion of said shunt member and of said armature, simultaneously, with respect to said stationary pole-piece.

2. In a lockout switch, in combination, a

10 movable armature, a magnet for actuating the armature, a holding magnet disposed to oppose the operation of the armature by the actuating magnet, a magnetic shunt looped around the holding magnet and extending be-

15 tween the magnet and armature and means for adjusting the magnetic shunt relative to the holding magnet to change the air gap between the holding magnet and armature thereby to control the operation of the ar-

20 mature.

3. In a lockout switch, in combination, a

movable armature, a magnet for actuating the armature, a holding magnet disposed to oppose the operation of the armature by the

25 actuating magnet, a magnetic shunt looped around the holding magnet, one arm of the magnetic shunt extending between the holding magnet and armature and means for adjusting said arm of the magnetic shunt relative to the holding magnet to vary the air gap between the shunt and holding magnet to control the operation of the armature.

4. In a lockout switch, in combination, a

35 movable armature, a magnet for actuating the armature, a holding magnet disposed to oppose the operation of the armature, a magnetic shunt simulating a clevis looped about the holding magnet, one arm of the shunt extending between the holding magnet and armature and means for adjusting the arms

40 of a shunt relative to one another to vary the air gap between the armature and holding magnet to control the operation of the armature.

45 In testimony whereof, I have hereunto subscribed my name this 29th day of December, 1925.

HAROLD E. WHITE.
